UNITED STATES PATENT OFFICE.

CLARENCE A. BERKINS, OF MINNEAPOLIS, MINNESOTA.

HYDROCARBON BURNER.

Application filed October 28, 1922. Serial No. 597,453.

My present invention relates to hydro-carbon burners adapted for general use in furnaces, boilers, stoves and the like, and is in the nature of an improvement on the burner 5 disclosed and claimed in my prior Patent No. 1,444,766 of date Feb. 6, 1923.

Generally stated, the invention consists of the novel construction and combinations of parts hereinafter described and defined in 10 the claims.

The present invention is directed particularly to the improvement of the generating cones, air intake tubes, and their relative arrangement in respect to each other and to the 15 basins below the cones.

In the accompanying drawings, which illustrate a commercial form of the improved burner, like characters indicate like parts throughout the several views.

20 Referring to the drawings:

Fig. 1 is a perspective with some parts broken away, showing a heater, such as a hot water heater or steam boiler, and illustrating the application of one of my 25 proved burners therein;

Fig. 2 is a plan view of the burner with some parts broken away and some parts removed; and

Fig. 3 is a vertical section of the burner 30 on the line 3—3 of Fig. 2.

Of the parts of the heater, the numeral 4 indicates the body shell, the numeral 5 the grates, and the numeral 6 the ash pit door opening, and from which latter the door has 35 been removed.

The complete burner, as preferably constructed, comprises a hollow cast base or box 7 of oblong form, open at its bottom, and closed at its top, except for a large central 40 air intake port 8 that is preferably approximately rectangular in form. On each side of the air port 8, the top plate of the base 7 is formed with depressed annular basins 9, from the centers of which rise hollow cones 45 10, which latter, however, are not the generating cones proper. Surplus oil overflow pipes 11 extend downward from the basins 9. Fluid fuel supply pipes 12 extend axially upward through the cones 10 and have 50 threaded engagement therewith and the threaded ends project above said cones to adjustably support the generating cones presently to be described.

The fuel supply pipes 12, in the arrangement illustrated, are provided with normally 55 open valves 13 having projecting arms 14

to which overflow pans or buckets 15 are attached. The overflow pipes 11, it will be noted by reference to Fig. 1, are arranged to deliver into these overflow pans. Also, 60 as shown, the two fuel pipes 12 are connected to a common supply pipe 16. The said arrangement of pipes and valves, however, constitutes no part of my invention.

The hollow base 7 rests on the grates 5 and 65 should be surrounded by ashes or any other suitable material, so that all of the air that passes through the fire box must pass upward through the central opening 8.

The numeral 17 indicates the upright rectangular body portion of the air intake stack, the lower end of which is open and fits downward through the air port 8 of the base 7. At its upper portion, said stack 17 has oppositely turned and downwardly extended air 75 tubes 18, the lower ends of which are located slightly above but concentric to the respective basins 9.

The vapor-generating cones 19 are preferably hollow cast structures that are spaced 80 from the cones 10 and are adjustably screwed onto the threaded upper ends of the fuel pipes 12. The exterior surfaces of said generating cones 19 are formed with circumferentially extended ledges of progressively increasing diameter. These ledges delay the 85 downward flow of the oil or fluid fuel and cause the latter to flow in ripples, which insures better and more complete vaporization of the fluid fuel.

A slight distance above the upper ends of the generating cones 19, the air tubes 18 are provided with internal annular ribs 20 that contract the diameter of the air passage and thereby cause the air tubes to act as Venturi 90 tubes in that the air will move more rapidly, as it passes through the contracted passages formed by said ribs 20, than it does at any other point higher up or further down, except at the place where the air moves radially outward through the escape passages formed between the extreme lower ends of said tubes 18 and the upper portions of the basins 9.

The vertical adjustability of the generating cones 19 in respect to the lower ends of the tubes 18 and in respect to the contracted passages formed by the ribs 20 is highly important because it permits the cones to be set for just the right adjustment to produce the most efficient generating and burning 100 action. Moreover, the said generating cones 110

are subjected to very intense heat and, hence, will require replacement from time to time and this replacement may be easily made by screwing the generating cones off from and onto the threaded upper ends of the fuel pipes 12. Furthermore, the said generating cones are spaced from the cones 10 so that they will be subjected to heat both on exterior and interior surfaces and, hence, will get hot quicker and will reach a higher temperature than with the arrangement, for example, illustrated in my prior patent wherein the generating cones on their interiors were exposed to the cool air.

15 The oil overflowing from the upper ends of the fuel supply tubes 12 will flow downward over the generating cones 19 in a manner already indicated, and when said generating cones are at high temperature, say red hot, the vaporization of the oil will be almost instantaneous. The contracted passages above the cones cause the air to move at relatively high velocity just as it comes into contact with the generated fuel vapor and then to move at slightly less velocity over the outer surfaces of the cones, and then finally to sweep outward again under high velocity as the ignited gases escape radially outward between the lower ends of the tubes 18 and the rims of the basins 19. These several features, I have found in actual practice, greatly increase the efficiency of the burner.

30 The burner illustrated is a duplex burner, but it will, of course, be understood that

so far as my present invention is concerned, the same might be a single burner.

What I claim is:

1. A fluid fuel burner comprising an air tube having a depending delivery end arranged for the downward delivery of air, a generating cone extended from a point below axially up into the delivery end of said tube but spaced therefrom, said air tube at a point slightly above said cone having an internal annular flange forming a contraction and causing the downwardly delivered air to be concentrated toward the top of said cone and to move with relatively high velocity, and means for delivering fluid fuel to the outer surface of said generating cone.

40 2. A burner comprising a base having an annular basin with a raised conical central portion, a fuel delivery pipe extended axially through said cone to a point above the same, a generating cone attached to the upper end of said fuel delivery pipe and surrounding but spaced from the raised conical portion of said basin, and an air tube having a depending end spaced from but surrounding the upper portion of said generating cone and arranged for the downward delivery of air around said cone and toward said basin, the downturned portion of said air tube having a contraction located close to but above the upper portion of said generating cone.

45 50 55 60 65 In testimony whereof I affix my signature.

CLARENCE A. BERKINS.
